RIVET APPLYING AND REMOVING TOOL

Joseph L. Rein, Washington, D. C.

Application December 19, 1949, Serial No. 133,769

5 Claims. (Cl. 78—46)

1

This invention relates to a tool especially designed for use in removing and in applying rivets on the door checks of certain makes of automobiles, but also having other uses.

In certain makes of automobiles the door checks are fastened to the body by means of rivets. To remove these, the usual practice is to knock them out as the space is very limited in which to work and the rivets are hard to get to. Ordinary rivet removing tools cannot be used and frequently damage is done which requires re-welding. With my tool, it is a simple and instantaneous job to punch out these rivets and thereby save considerable time. With the same tool, I am also able to easily and very quickly replace and secure the rivets.

It is, therefore, an object of this invention to provide a rivet tool which will make it easy to remove or replace rivets, the tool being formed of a pair of pivoted jaws with relatively long handles so that sufficient pressure may be exerted to perform the required operation.

Another object of this invention is to provide a rivet tool which can be quickly converted from a rivet removing tool to a rivet applying tool. One of the jaws is provided with a slot through which the rivet being removed is adapted to pass, and when a rivet is to be applied or replaced, the slot is covered by a sliding anvil or abutment which is carried by the slotted jaw, and at this time the removing pin is reversed to present a rivet upsetting head to the anvil.

With the above and other objects in view, my invention consists in the arrangement, combination and details of construction disclosed in the drawings and specification, and then more particularly pointed out in the appended claims.

In the drawings:

Figure 1 is a detailed plan view partly broken away and in section of a rivet removing and applying tool constructed according to an embodiment of this invention.

Figure 2 is a fragmentary longitudinal section of the tool in rivet upsetting position.

Figure 3 is a fragmentary side elevation of the tool in rivet removing position.

Figure 4 is a fragmentary sectional view taken on the line 4—4 of Figure 3.

Figure 5 is a detailed front elevation of the tool in the position shown in Figure 3.

Figure 6 is a sectional view taken on the line 6—6 of Figure 3.

Referring to the drawings, the numerals 10 and 11 designate generally a pair of jaw members which are pivotally connected together, the jaw member 10 being provided with a pair of ears 12 between which the rear end of jaw 11

2

engages, and a pivot member 13 engages through the ears 12 and the rear portion of jaw member 11. Jaw member 10 has extending rearwardly therefrom an elongated handle 14 which is fixed relative to the jaw 10, and jaw member 11 has pivotally mounted thereon a handle or lever 15.

The forward end of the handle or lever 15 rockably engages between a pair of ears 16 carried by the jaw member 11 forwardly of the pivot 13 and a pivot 17 engages through the ears 16 and the forward end of handle or lever 15. A laterally offset lever 18 is fixedly carried by the handle 15 projecting forwardly of the pivot 17, and a pair of links 19 are pivotally secured as by a pivot 20 to the lever 18 and are pivotally secured as by a pivot 21 to the jaw member 10 at a point closely adjacent the forward end of jaw member 10.

Jaw member 10 is formed with an inwardly opening socket 22 adjacent the forward end thereof and a relatively small diameter opening 23 extends from the bottom of the socket 22 as shown in Figure 2. A rivet engaging pin 24 is removably mounted in the socket 22 and includes a relatively large diameter body 25 formed with a rivet upsetting head 26 which is adapted to project from the inner face of jaw member 10.

A relatively small diameter shank 27 extends from the body 25 oppositely from the head 26 and terminates in a relatively small diameter stud 28. The shank 27 is adapted to engage through the opening 23 as shown in Figure 2 when the tool is used for applying a rivet.

The jaw 11 has slidably mounted thereon an anvil 29 constructed in the form of an elongated plate which is formed with a longitudinally extended elongated opening or slot 30 through which a securing member 31 engages for slidably mounting the anvil or plate 29 on the inner face of jaw member 11. The plate or anvil 29 has extending from the opposite lengthwise edges thereof pairs of lugs 32 which engage on the opposite sides of jaw member 11 for holding the anvil or plate 29 against lateral movement.

Jaw member 11 is provided at the forward end thereof with a forwardly opening slot 33 within which the shank 27 of the rivet engaging tool 24 is adapted to loosely engage when the rivet engaging member 24 is reversed as shown in Figure 3. With rivet engaging member 24 reversed or in rivet removing position the head 26 will be disposed innermost with respect to the socket 22, and the small stud 28 will engage with the rivet so that when pressure is applied to the handles 14 and 15 so as to rock jaw member 11 toward jaw member 10, the rivet will be pushed out of the work and into the slot 23. At this

time the anvil 29 will be in a retracted position as shown in full lines in Figures 3 and 4.

In the use and operation of this device when it is desired to remove a rivet the rivet engaging member 24 is mounted in the socket 22 of jaw 10 with the body 25 innermost and the shank 27 projecting in the direction of jaw member 11.

The stud 28 is engaged with the end of the rivet, preferably the upset end of the rivet, and pressure is then applied to the handle levers 14 and 15. These handles or levers are of sufficient length so that sufficient pressure or leverage will be obtained to forcibly remove the rivet. When the new rivet is to be replaced the anvil 29 is moved forwardly to a position overlying the slot 22, and the rivet engaging member 24 is reversed to the position shown in Figure 2.

The upsetting head 26 will engage the rivet end, and upon pressure being applied to the handles or levers 14 and 15, the rivet will be upset and tightly secured in the work.

As shown in Figure 1 handle or lever 15 constitutes a magazine being formed at its rear end with an elongated bore 34 within which rivet engaging members are adapted to engage, and the bore 34 is normally closed by means of a threaded plug 35.

The anvil 29 is frictionally held in adjusted position either overlying the slot 33 or in a rear inoperative position by means of a spring 34 which is interposed between screw 31 and the anvil 29. In this manner the anvil cannot accidentally move out of its adjusted position.

What is claimed is:

1. A rivet tool comprising a pair of pivoted jaws, a handle fixed to one of said jaws, a second handle pivoted to the other jaw forwardly of the pivotal connection between the jaws, an offset lever carried by the second handle projecting forwardly of the pivotal connection of said second handle, a pair of links pivotally secured between said lever and said one jaw, a rivet engaging pin carried by said one jaw and projecting therefrom in the direction of said other jaw, said other jaw having a slot in the forward end thereof within which the projecting portion of said pin is loosely engageable when the jaws are closed, an anvil plate having an elongated slot therein positioned on the underside of said other jaw and means extending through said last mentioned slot releasably securing said anvil to said jaw to permit linear movement thereof relative to said jaw selectively to close or open said first mentioned slot.

2. A rivet tool comprising a pair of pivoted jaws, a handle fixed to one of said jaws, a second handle pivoted to the other jaw forwardly of the pivotal connection between the jaws, an offset lever carried by the second handle projecting forwardly of the pivotal connection of said second handle, a pair of links pivotally secured between said lever and said one jaw, said one jaw having a socket opening through the inner face thereof and a reduced diameter opening extending outwardly from the bottom of said socket, and a reversible rivet engaging pin formed with a body engageable in said socket and with a shank engageable in said opening, said body having a rivet upsetting head on the end thereof opposite from said shank, said shank upon reversal of said pin projecting from the inner face of said one jaw and constituting a rivet removing member, said other jaw having a slot in the forward end thereof within which said shank is adapted to loosely engage when the

jaws are closed, an anvil plate having an elongated slot therein positioned on the underside of said other jaw and means extending through said last mentioned slot releasably securing said anvil to said jaw to permit linear movement thereof relative to said jaw selectively to close or open said first mentioned slot.

3. A rivet tool comprising a pair of pivoted jaws, a handle fixed to one of said jaws, a second handle pivoted to the other jaw forwardly of the pivotal connection between the jaws, an offset lever carried by the second handle projecting forwardly of the pivotal connection of said second handle, a pair of links pivotally secured between said lever and said one jaw, a rivet engaging pin carried by said one jaw and projecting therefrom in the direction of said other jaw, said other jaw having a slot in the forward end thereof within which the projecting portion of said pin is loosely engageable when the jaws are closed, an anvil plate having an elongated slot therein positioned on the underside of said other jaw and means extending through said last mentioned slot releasably securing said anvil to said jaw to permit linear movement thereof relative to said jaw selectively to close or open said first mentioned slot, said anvil plate being substantially the width of said other jaw, and lugs extending from the sides of said anvil plate along the sides of said jaw to maintain the alignment of said anvil and said jaw.

4. A rivet tool comprising a pair of opposed jaws, a handle secured to one of said jaws, linkage between said jaws and a second handle pivotally secured to said other jaw, and said linkage to move said jaws toward and away from each other, one of said jaws having a slot therein, an anvil plate having an elongated slot therein positioned on the face of said one of said jaws, means extending through said slot releasably securing said plate to said face for linear movement therealong whereby said plate may be moved selectively to close or open said first mentioned slot, said other jaw having a socket therein and a reversible rivet engaging pin in said socket.

5. A rivet tool comprising a pair of opposed jaws, a handle secured to one of said jaws, linkage between said jaws and a second handle pivotally secured to said other jaw, and said linkage to move said jaws toward and away from each other, one of said jaws having a slot therein, an anvil plate having an elongated slot therein positioned on the face of said one of said jaws, means extending through said slot releasably securing said plate to said face for linear movement therealong whereby said plate may be moved selectively to close or open said first mentioned slot, lugs extending from the sides of said plate along the sides of said one jaw to maintain said plate in said jaw in alignment, said other jaw having a socket therein and a reversible rivet engaging pin in said socket.
